ROLLING MECHANISM

Abraham Simons, New York, N. Y.

Application May 19, 1937, Serial No. 143,406

3 Claims. (Cl. 80—31.1)

My invention relates to a new and improved method of rolling material, and to a new and improved rolling mechanism.

My invention relates particularly to the cold-rolling of metal stock, although it is not restricted to any particular type of rolling.

The invention is particularly valuable for rolling sheet metal stock which is relatively wide and which ordinarily has a starting width of more than one (1") inch.

The invention is particularly useful in connection with the rolling of wide stock having a width of between six (6") inches and sixty (60") inches.

In rolling wide stock by means of an ordinary rolling mill, the thickness of the stock is reduced at each pass, but the increase in the width of the stock is practically negligible.

The invention relates particularly to the rolling of stock whose width is so great as to make the increase in width negligible during the rolling operation.

However, the invention is useful in connection with the rolling of all metal stock, even of small width.

A particular object of the invention is to provide a sufficient back-pull on the stock, anterior to the first pair of mill rolls, so as to lower the effective or screw pressure which is exerted upon the first pair of mill rolls so as to force the shafts of said mill rolls towards each other.

Another object is to diminish said pressure upon the mill rolls and likewise to diminish the extrusion effect of said mill rolls.

Another object of the invention is to accomplish said purposes, or one or more of them, while minimizing the power consumption, and even practically eliminating the increased power consumption which results ordinarily by exerting a back-pull upon the stock, anterior to the first pair of mill rolls. The invention may also be applied anterior to the second pair of mill rolls and anterior to each of the successive pairs of mill rolls, if desired.

Other objects of the invention will be stated in the annexed description and drawing which illustrate one form of mechanism for utilizing the invention.

It will be understood that the drawing is largely diagrammatic.

Fig. 1 is a side elevation showing the improved machine.

Fig. 2 is a top elevation of Fig. 1.

Fig. 3 is a partial side elevation of Fig. 1, show-

ing the side opposite to that which is shown in Fig. 1.

The drawing shows a pair of mill rolls 1 and 2 which may be of any suitable type. I have not shown the screws or other devices for forcing the shafts of the mill rolls towards each other in order to exert the rolling pressure upon the stock, as such pressure devices may be of any conventional type.

The bottom mill roll 2 has its shaft provided with a bevel gear 9 which meshes with the bevel gear 8. This bevel gear 8 is mounted upon a shaft which is supported in a suitable bearing B. Said shaft is connected by means of a suitable friction clutch 7, to a shaft of a gear box G, which may be of any suitable speed change type.

The shaft of the bevel gear 6 is also mounted in a bearing B and it is driven from a shaft of the gear box G. The gear box G is provided with the usual lever 1a in order to regulate the speed ratio between the shaft of the bevel gear 6 and the shaft of the metal disc 7b of the friction clutch 7. Said friction clutch 7 is of the usual type having metal discs 7b and 7c, between which there are a suitable number of friction discs which are held pressed against each other. The friction clutch may be of any well known type, and any type of coupling which has the function of a friction clutch may be substituted for said clutch.

This coupling may be designated as a slip-coupling because it permits the shafts of the equal gears 6 and 8 to turn at different angular speeds so that said shafts turn at different revolutions per minute.

In this embodiment the bevel gears 6 and 8 have the same pitch diameters. The shafts of said gears 6 and 8 can be turned at different angular speeds, or at different numbers of revolutions per minute, by means of the speed change mechanism and the slip-coupling. This difference in angular speed may be small. Assuming that the bevel gears 6 and 8 have the same pitch diameters, the shaft of one said bevel gear may turn 101 revolutions or 102 revolutions, while the shaft of the other bevel gear turns 100 revolutions. Hence, the difference in peripheral speed between the equal bevel gears 6 and 8 may be only 1% or 2%. This difference in speed may be greater, up to any desired limit.

The bevel gear 6 drives the bevel gear 5, which is keyed to the shaft of the first retarding member 4. Said retarding member 4 is shaped like an ordinary disc or pulley. The shaft of the retarding member 4 is provided with a spur-gear 4a

30

35

35

50

50

55

which meshes with the equal spur-gear 3a of the shaft of the second retarding member 3. The retarding members 3 and 4 are of identical shape and diameter. Said retarding members 3 and 4 5 may have different diameters, as long as they have the same peripheral speeds.

The stock S is led through a suitable adjustable friction member F which applies an initial and relatively small frictional retarding effect 10 upon the stock S. Any other device for producing a regulated retarding effect may be used.

The retarding effect of device F causes the stock to have firm frictional contact with the connected retarding members 3 and 4, so that 15 there is little or no slip between the stock and the train of retarding members.

Instead of having only two retarding members 20 3 and 4, I can have any desired number, so as to increase the total frictional retarding effect which is produced by the member F and the train of interconnected retarding means.

The peripheries of the retarding members 3 25 and 4 are made of any suitable material such as steel or other material, so that there is a suitably high coefficient of friction between the stock and the peripheries of the retarding members 3 and 4. However, there may be some slipping between the stock and the retarding members, without 30 making the device inoperative or non-commercial.

The shafts D and D' of the mill rolls are driven through a common gear box, by a single motor. This drive for the mill rolls 1 and 2 is not shown in the drawing, because it may be a conventional drive. The mill rolls 1 and 2 are driven at 35 the same peripheral speed.

It has previously been found that if a retarding and tension effect is imposed upon the stock anterior to the mill rolls, this makes it possible 40 to reduce the stock between the mill rolls with the use of less pressure upon said mill rolls.

If the retarding effect is very high, such as 45 for example, between ten thousand (10,000) pounds and fifty thousand (50,000) pounds per square inch of the cross section of the stock, if this is steel, this high retarding effect makes it possible greatly to diminish the pressure upon the mill rolls. The retarding force may be close to and almost equal to the elastic limit of the 50 reduced stock which leaves the mill rolls. The pressure upon the mill rolls may be diminished as high as twenty-five (25%) per cent to thirty-five (35%) per cent of the pressure which is required, if there is no substantial retarding effect.

Likewise the use of such a high retarding force 55 diminishes the extrusion effect of the mill rolls upon the stock. When the rolls reduce the thickness of the stock, they produce in part an extrusion effect, similar to the effect which is 60 produced when material is forced through a die in order to shape the material.

However, the use of such high retarding force 65 has greatly increased the power consumption of the mill rolls, due to the fact that the mill rolls were compelled, not only to roll and reduce the stock, but also to pull it against a very high retarding force which was exerted solely by friction means, which remained stationary during 70 the operation of the mechanism. Therefore the loss in power due to the retarding effect of such friction means, counterbalanced the decrease in power which was secured by the lowering of the reducing or rolling pressure on the mill rolls.

According to this invention, the stationary 75

adjustable friction means F need produce only a very small back-pull.

It is desirable to have the stationary friction means F produce as little as possible of the retarding effect (much less than fifty per cent), and to have as much as possible of the retarding effect produced by the turnable or movable means 3 and 4.

Since the turnable retarding means 3 and 4 are connected to the shaft of one of the mill rolls, 10 by means of a slip-coupling or friction clutch, the pull of the stock on said members 3 and 4 is transmitted through the friction clutch or slip-coupling to the mill rolls, so that there is little or no loss of power due to the retarding 15 effect of the members 3 and 4. The stock is pulled by the mill rolls 1 and 2. The friction clutch 7 slips continuously or substantially continuously, during the operation of the device. However, the amount of slip is small because the 20 difference of angular speed between the shafts of the gears 6 and 8 is small. The wear of the friction clutch 7 is therefore slight.

It will be noted that the mill roll 2 and the retarding member 4 turn in opposite directions 25 so that the rotation of the retarding member 4 tends to drive the mill roll 2, so that the top of the periphery of the mill roll 2 is driven in the same direction as the stock. The directions of turning of the rotatable parts are indicated by 30 the arrows in Fig. 1.

The adjusting lever 7a may be set so as to regulate the ratio of speeds between the shafts of the bevel gears 6 and 8, in accordance with the 35 diameters of the peripheries of the mill rolls and of the retarding members, and the amount of reduction in thickness of the stock, so that the speed of the stock, anterior the mill rolls, is less than the peripheral speed of the mill rolls 1 and 2.

Likewise, the speed of the stock S, anterior to the mill rolls 1 and 2, is less than the speed of the stock which would be secured by free feeding. By free feeding, I mean a condition in 45 which the stock is fed freely to the mill rolls 1 and 2 and without any substantial retarding effect.

If the speed-change lever 7a were set so that 50 members 1, 2, 3 and 4 would have the same peripheral speed, the stock could be reduced to some extent between the mill rolls 1 and 2, without changing the width of the stock. Said reduction in thickness of the stock, under such conditions, would cause a buckling of the stock 55 anterior to the mill rolls, if the width of the stock would remain the same, after the reduction in thickness of the stock.

As a working example, I may assume that the thickness of the stock is reduced twenty-five per cent (from a thickness of .100 inch to 0.075 60 inch) in the first pass between the equal mill rolls 1 and 2, and without substantially changing the width of the stock. The speed-change lever should then be adjusted so that the peripheral speed of the retarding members 3 and 4, and the 65 equal linear speed of the stock anterior the first pair of mill rolls 1 and 2, should be less than seventy-five (75%) per cent and about seventy-four (74%) per cent of the equal peripheral speeds of rolls 1 and 2. This will not only prevent buckling, but will cause the pull of the stock which is produced by the mill rolls, to drive the members 3 and 4, so that said pull of the stock is transmitted through members 3 and 4, gears 5 and 6, the gears of box G, the friction clutch or 70 75

slip-coupling, and gears 8 and 9, positively to help drive the mill rolls, while the friction clutch or slip-coupling will slip sufficiently to compensate for the difference in peripheral speed between members 3 and 4, and mill rolls 1 and 2.

It will be noted that due to the extrusion effect on the stock of the mill rolls, the reduced stock leaves the mill rolls at a speed slightly higher than the peripheral speed of said mill rolls. This extrusion effect is diminished as much as possible according to my invention, by the back pull which is exerted anterior to the mill rolls 1 and 2, but some extrusion effect may exist.

Assuming that the thickness of the stock is reduced twenty-five (25%) per cent, without changing the width of the stock, said reduction in thickness will increase the length of the stock by thirty-three and one-third (33 1/3%) per cent. The peripheral speed of the mill rolls will ordinarily be a trifle less than the speed of movement of the reduced stock away from the mill rolls, so that the linear speed of movement of the stock anterior and towards the mill rolls would be about seventy-five (75%) per cent of the peripheral speed of the mill rolls, if no substantial retarding effect were created.

Therefore, by having the peripheral speed of members 3 and 4 less than seventy-five (75%) per cent of the peripheral speed of mill rolls 1 and 2, I can secure a retarding effect, because there is little or no slip of the stock relative to the retarding members 3 and 4. Said members 3 and 4 are made of sufficiently large diameter, and I provide a sufficient number of said retarding members (more than two, if desired) to minimize or prevent said slipping. This lowering in peripheral speed of the retarding members 3 and 4 relative to the peripheral speed of the mill rolls, depends upon the kind of stock, and other working conditions, such as the percentage of reduction.

Therefore, and assuming that the apparatus is running idle, because no stock is being fed thereto, the lever 1a may be set so that the peripheral speed of members 3 and 4 is less than seventy-five (75%) per cent of the peripheral speed of mill rolls 1 and 2, assuming that mill rolls 1 and 2 are set to accomplish a reduction in thickness of the steel stock of twenty-five (25%) per cent, and without changing the width of the stock.

Now, if stock is fed through the machine, after such adjustment has been made, the pull of the stock which is produced by the mill rolls, tends to turn members 3 and 4 at about seventy-five (75%) per cent of the peripheral speed of mill rolls 1 and 2, since the linear speed of the stock anterior to and towards mill rolls 1 and 2, tends to be about seventy-five (75%) per cent of the peripheral speed of mill rolls 1 and 2, in the example given.

Since the setting of the gear box G remains as previously mentioned, the pull of the stock tends to turn the members 3 and 4 more rapidly than when the machine was operating without stock, thus producing an overdrive of members 3 and 4, which causes the friction clutch to slip, while returning to the mill rolls, nearly all the power which would otherwise be lost in over-coming the back pull.

The connection between the turnable retarding members 3 and 4 and the mill rolls consists wholly of gears and a friction clutch. While the apparatus is operating, the gear connection is regulated so that the clutch 7 slips slightly but

continuously. The tension of the stock S, anterior the mill rolls, causes said stock to operate like a drive-belt, which urges the retarding discs to move in the directions of the respective arrows which are shown in Fig. 1. This overdrive which is produced by the tension of the stock is transmitted through the gears and the slipping clutch to the mill rolls, so as to transmit to said mill rolls the power which otherwise would be lost in exerting the back-pull. The invention is not limited to the use of a friction clutch.

It will be noted that the speed of movement of the stock towards the mill rolls is not constant. The stock varies in thickness and hardness, so that the speed of movement of the stock, due to the pull of the mill rolls, varies continuously and sharply. However, the friction clutch or slip-coupling allows for variations in the speed of the stock towards the mill rolls, and for the consequent variations in the strength of the pull which is exerted on the stock by the mill rolls.

If a friction clutch is used, the member 7b will turn more rapidly than member 7c, but this difference in turning speed can be very small, so that there is little loss of energy, and little wear upon the friction clutch.

It has heretofore been proposed to connect the shafts of mill rolls, and the shafts of turnable friction members located anterior the mill rolls, and which controlled the speed of feed of the stock towards the mill rolls, wholly by gears.

The controlling factor in such system was the gear connections.

In the present method and device, the controlling factor is the pull which is exerted by the mill rolls upon the stock. Gear connections can be omitted wholly between the retarding means and the mill rolls, and said gear could be replaced by friction drive means, electromagnetic drive means, etc.

The all-gear connection produced a constant speed of the stock towards the rolls. In the instant embodiment, the speed of the stock can vary to the same extent as though no retarding means were used, save for the effect of the inertia of the retarding means.

The driving means between the retarding means and the mill rolls may be designated as overdrive means, since they cause the pull of the stock which is produced by the mill rolls to drive said mill rolls.

I claim:

1. Rolling mechanism comprising turnable mill rolls having movable means located anterior to the mill rolls and located so that the stock contacts with said movable means anterior the mill rolls, the entering portion of the stock being located anterior said movable means, said movable means being shaped so that they are driven by the movement of the stock when the stock is pulled by the mill rolls, said movable means being connected to said mill rolls by overdrive means, so that the pull on the stock which is produced by the mill rolls, operates to drive the mill rolls, said overdrive means including slip-coupling means having separated members connected to be free to turn at different relative speeds.

2. Rolling mechanism comprising turnable mill rolls, said mechanism also having rotatable retarding means located anterior said mill rolls so that the stock contacts with said retarding means anterior the mill rolls, said stock having only a single layer thereof in contact with said

retarding means, braking means for the stock located anterior said rotatable retarding means, said retarding means being connected to said mill rolls by connecting means which consist wholly of gears and a slip device, said gears being adapted to turn said retarding means at lower peripheral speed than the speed at which the stock is fed by the mill rolls away from said rotatable retarding means, so that the stock is subjected to tension between the mill rolls and said retarding means.

3. Rolling mechanism comprising turnable mill rolls, said mechanism also having rotatable retarding means located anterior said mill rolls so that the stock contacts with said retarding

means anterior the mill rolls, said stock having only a single layer thereof in contact with said retarding means, braking means for the stock located anterior said rotatable retarding means, said retarding means being connected to said mill rolls by connecting means which consist wholly of gears and a slip friction clutch, said gears being adapted to turn said retarding means at lower peripheral speed than the speed at which the stock is fed by the mill rolls away from said rotatable retarding means, so that the stock is subjected to tension between the mill rolls and said retarding means. 5 10

ABRAHAM SIMONS.
